UNITED STATES PATENT OFFICE.

JOHN GOLDSBOROUGH, OF PHILADELPHIA, PENNSYLVANIA.

DESIGN FOR A WATCH-KEY OR CHARM.

Specification forming part of Design No. 5,757, dated April 9, 1872.

Specification describing a Design for a Watch-
Key or Charm, produced or invented by JOHN
GOLDSBOROUGH, of the city and county of
Philadelphia, State of Pennsylvania.

My design is fully illustrated by the enlarged
perspective view in the accompanying draw-
ing; and consists of a miniature representation
of a hand-stamp or stamp-canceling machine,
formed of gold or other metal, and having se-
cured to it a watch-key stem, *a*, and an eye, *b*,
by means of which it may be secured to a watch-
chain.

The stem *a* is not an essential feature of the
design, and may be dispensed with, the minia-

ture hand-stamp forming, in such case, merely
a trinket or charm for the watch-chain.

I claim—

The design for a watch-key or charm, sub-
stantially as described, and as represented in
and by the accompanying drawing.

In testimony whereof I have signed my name
to this specification in the presence of two sub-
scribing witnesses.

JOHN GOLDSBOROUGH.

Witnesses:

WM. A. STEEL,
HARRY W. DOUTY.
